United States Patent Office

Des. 189,619
Patented Jan. 17, 1961

189,619

ELECTRIC CONTROL UNIT

George Barradas, Glenville, Conn., assignor to Bobrich
Products Corp., New York, N.Y., a corporation of
New Jersey

Filed May 18, 1959, Ser. No. 55,939

Term of patent 14 years

(Cl. D26—13)

Fig. 2.

Fig. 1.

Fig. 3.

Fig. 4.

Fig. 1 is a front elevational view of an electric control unit, showing my new design;

Fig. 2 is a top plan view thereof;

Fig. 3 is a side view thereof; and

Fig. 4 is a rear view thereof.

The dominant feature of the design resides in the portion shown in full lines.

I claim:

The ornamental design for an electric control unit, substantially as shown and described.
